(57) **CLAIM**

The ornamental design for a weighted apparel article, as shown and described.

DESCRIPTION

FIG. 1 is a front view of a weighted apparel article according to a first embodiment of the claimed design.

FIG. 2 is a rear view of the weighted apparel article of FIG. 1.

FIG. 3 is a right side view of the weighted apparel article of FIG. 1.

FIG. 4 is a left side view of the weighted apparel article of FIG. 1.

FIG. 5 is a front view of a weighted apparel article according to a second embodiment of the claimed design.

FIG. 6 is a rear view of the weighted apparel article of FIG. 5.

FIG. 7 is a right side view of the weighted apparel article of FIG. 5; and,

FIG. 8 is a left side view of the weighted apparel article of FIG. 5.

The broken lines in the drawings represent stitching that forms no part of the claimed design.

1 Claim, 8 Drawing Sheets
